UNITED STATES PATENT OFFICE.

LEWIS A. BRINKMAN, OF CHICAGO, ILLINOIS.

MUSIC-HOLDER.

1,009,043.

Specification of Letters Patent. Patented Nov. 21, 1911.

Application filed March 20, 1911. Serial No. 615,563.

To all whom it may concern:

Be it known that I, LEWIS A. BRINKMAN, a citizen of the United States, residing at Chicago, county of Cook, State of Illinois, have invented certain new and useful Improvements in Music-Holders, of which the following is a specification.

The present invention relates generally to music holders for use in supporting sheet music and the like, and more particularly to that class of holders having collapsible and foldable stands and racks which enable the holder to be folded together into a compact parcel.

The object of the invention is to provide an improved holder of this class, which, as compared with holders of the prior art, will be stronger and more durable in service, more economical to manufacture, and relatively more compact when collapsed and folded.

To this end, it consists in certain novel features of construction and arrangement of parts which will best be understood upon reference to the following detailed description, taken in connection with the accompanying drawing, the novelty being particularly pointed out in the appended claims.

In the drawings, Figure 1 is a front elevation of a music holder constructed in accordance with the present invention; Fig. 2 is an enlarged partial sectional view of the lower end of the standard, illustrating the mechanism for holding the legs distended; Fig. 3 is a sectional view illustrating a frictional joint between the sections of the standard; Fig. 4 is a cross-section of one of the legs; Fig. 5 is a side elevation of the pivotal connection between the rack and the upper end of the standard, a portion of the rack being shown in section upon a plane indicated by the line 5—5 of Fig. 1; Fig. 6 is a plan view of the same; Fig. 7 is a sectional view taken on a plane indicated by the line 7—7 of Fig. 1; and Fig. 8 is a sectional view illustrating a second frictional joint between the sections of the standard.

Throughout these figures, like characters refer to like parts.

Referring to the drawing in detail, 10 designates the standard, 11 the legs by which it is supported, and 12 the rack upon which the music, or the like, is to be supported. The standard 10 is composed of a number of telescoping sections—in the present case, 55 five sections designated 13, 14, 15, 16 and 17. When these sections are telescoped, the section 17 is outermost, and section 13 is innermost. The rack 12 is secured to the upper end of the uppermost section 13, while the 60 legs 11 are associated with the lowermost section 17. In the present instance, three legs are employed. Each leg consists of a metal punching folded so as to provide a U-shaped cross-section, as illustrated in Fig. 4, and so as to provide for the inclosing of the associated braces 18. The inner end of the legs are pivoted to a collar which is made up of three punchings 19. In assembling these punchings and the legs, the pivots 20 serve both to fasten the punchings together and to pivotally secure the inner ends of the legs. The collar, formed by these punchings 19, is slidable upon the section 17 of the standard. A similar collar 21, also composed of three punchings, is secured to the section 17 near its lower end. The pivots 22, which fasten these punchings together, also pivotally secure the inner ends of the brackets 18. The outer ends of 80 these brackets are secured to intermediate points of the legs 11 by pivots 23. With this construction, it will be seen that as the slidable collar, composed of the punchings 19, is moved upward, the legs 20 will be 85 brought into proximity to the standard section 17 in much the same way that an umbrella is collapsed. In order to hold the legs distended, the punchings 19 are made with downwardly projecting portions which serve 90 as leaf-spring catches. These catches are provided with suitable shoulders 24, 25, to engage the collar 21, as clearly illustrated in Fig. 2. When thus engaged, the legs cannot be moved, but rigidly support the 95 standard. In order to readily release the catches, of which there are preferably three, the lower end of the section 17 is provided

with a ring 26 which has a limited up-and-down movement upon the section, by reason of a pin 27 secured at its ends to the ring 26 and extending through the slots 28 in the 5 walls of the tubular section. When the ring 26 is pushed upward by hand, it engages the inclined faces at the ends of the catches and causes them to disengage the collar 21 so that the slidable collar may be 10 readily moved to collapse the legs of the device. In order that the standard may remain in the positions to which it is adjusted, its several sections frictionally engage 15 each other. Such frictional engagement may be brought about in many different ways. In Fig. 3, however, I have illustrated one construction for providing frictional engagement. Here two sections, which we 20 may assume to be sections 13 and 14, are shown. The lower end of section 13 has a ring 29 secured to its outside. The upper end of the section 14 is contracted, as illustrated at 30, so as to closely engage the section 13. This construction provides a close 25 fit between the overlapping portions of the two sections and prevents one being drawn out of the other. A saw-cut 31 provides the proper resiliency to enable the sections to be drawn out or forced together.

30 The rack 12, as before stated, is pivotally secured to the upper end of the uppermost section 13 of the standard. As illustrated in Figs. 5 and 6, a lateral projection 32 extends from the upper end of the section 13 and is provided by a punching which is 35 fitted closely about the upper end of the section 13 and extends between the projecting leaves 33 secured to the back of the central vertical member 34 of the rack by pivots 35, 40 36. A pivot 37 unites the projection 32 and leaves 33 and consequently provides a pivotal connection between the standard 10 and rack 12. It will also be noted that in the construction here shown, the forward end 45 of the projection 32 extends through a slot in the lower end of the central vertical member 34. Pivots 36, in addition to securing the leaves 33 to the central vertical member 34, also serve to connect the lower horizontal 50 members 38 to the member 34. Similar upper longitudinal members 39 extend outward from the member 34, to which they are secured by pivots 40. The members 38 are also provided with outer vertical 55 members 41, which are pivoted at points intermediate of their length to the lower horizontal members 38 by pivots 42. These outer vertical members 41 and the upper horizontal members 39 are provided, respectively, with extension members 43 and 60 44. The members 43 are pivoted at their lower ends to the upper ends of the members 41 by pivots 45, and the members 44 are pivoted at their inner ends to the outer ends of the members 39 by pivots 46.

These extension members 43, 44, also cross each other intermediate of their lengths and are pivoted together at such points by pivots 47. Links 48 are secured by pivots 49 to the lower horizontal members 38 at points 70 adjacent to their inner ends. These links, together with the lower ends of the outer vertical members 41, serve to support the shelf sections 50 through the agency of pivots 51, 52. The central vertical member 34 75 is also provided with slots 53. These slots serve to guide and to limit the movement of pivots 54, which extend through the adjacent ends of the braces 55, 56. The upper braces 55 are connected at their opposite 80 ends by pivots 57 to the upper horizontal members 39, and braces 56 are connected at their lower ends to the lower horizontal members 38 by pivots 49.

In lieu of the construction of Fig. 3 for providing frictional engagement between the sections of the standard, I may employ the construction of Fig. 8. In this figure, sections 15 and 16 are illustrated. Section 16 is contracted at its upper end, as illustrated at 58, so as to closely engage the section 15. Section 15, in turn, is enlarged at its lower end, as at 59, so as to closely engage the inside of the section 16. A short saw-cut 60 is also made in the lower end of 95 the section 15. A pin 61 passes through openings in the expanded portion 59 of the section 15. It is provided to engage the section which slides into section 15 and the saw-cut enables the lower end of the section 100 15 to yield as it is moved within section 16. The pin 61 is loosely fitted in the expanded portion 51 of section 15 so as not to interfere with its resiliency, and it is of such length as to not engage the inner surface of 105 section 16 as the section 15 is moved within it. Section 15 is also provided, at some little distance from its lower end, with an expanded portion or bead 62 which engages the inner surface of section 16 and is adapted to abut against the contracted end 58 to 110 stop the outward movement of section 15. Obviously, the constructions of either Figs. 3 or 8 might be used throughout the standard in order to provide proper frictional engagement between the sections, or the construction of one figure might be employed in the case of certain sections, and that of the other in the case of other sections in the same standard. The construction of Fig. 8, 115 however, is preferable to that of Fig. 3.

In carrying out my invention, I have sought to construct the rack, standard and legs in such a manner as to bring them all within a relatively small compass when the holder is collapsed and reduced to its smallest dimensions and, from the above description, it will be seen that such a device has been provided. When collapsed, the telescoping sections occupy a length substan- 120 130

tially the same as the lowermost section. The same is true of the legs. When the central vertical member 34 is moved about its pivot 37 so as to bring its front face into engagement with the collapsed standard, it, too, is of a length less than the lowermost section of the standard. Likewise, a collapsing of the various members of the rack on either side of the central vertical member do not increase the length of the collapsed device beyond that of the lowermost section of the standard. In view of this, I am able, with the particular embodiment of the invention here illustrated, to construct a holder which shall have the usual size of rack and height of stand when expanded and will occupy a length of not more than twelve inches when folded. From the above description, it will also be seen that the horizontal members 38 and 39 are rigidly held by the braces 55 and 56. This provides a rigid and substantial structure which is bound to maintain these members horizontal, even though the pivots be considerably worn. It will also be observed that by reason of the shelf sections being hung from the horizontal members 38, which are thus rigidly held, such sections will be maintained in alinement, even though the parts become considerably worn by use. In view of this hanging of the shelf sections, there will also be no sagging or drooping of the corners of the holder because of wear. The weight of the book or music upon the shelf sections will tend to maintain the members 41 and 43 vertical and thereby bring the horizontal extension members 44 into line with the upper horizontal members 39.

What I claim as new and desire to secure by Letters Patent of the United States is:—

1. A collapsible music holder comprising a standard composed of telescoping sections, a collapsible rack secured to the upper end of the uppermost of said sections, a slideable collar on the lowermost of said sections, legs pivoted to said collar, braces pivoted at one end to said legs and at the other end to said lowermost section at a point below said collar, a leaf-spring catch extending downward from said collar and formed integral with a portion of it, means upon said lowermost section below said collar for engaging said catch to lock said legs in distended position, and a slideable member upon the lower end of said lowermost section for engaging said catch to free it from said engaging means to allow said legs to be collapsed by sliding said collar upward along said lowermost section.

2. A collapsible music holder comprising a standard composed of telescoping sections, a collapsible rack secured to the upper end of the uppermost of said sections, a slideable collar on the lowermost of said sections composed of a plurality of punchings fastened

together, legs pivoted to said collar at the points where said punchings are fastened together, a similar collar composed of punchings fixed to said lowermost section at a point beneath said slideable collar, braces pivoted to said fixed collar at one end and to intermediate points upon said legs at the other end, a leaf-spring catch formed integral with one of the punchings of said slideable collar and extending downward therefrom into a position to engage said fixed collar when said legs are distended by the downward movement of said slideable collar, and a slideable member upon the lower end of said lowermost section for engaging said catch to free it from said fixed collar to allow said legs to be collapsed by sliding said movable collar upward along said lowermost section.

3. A collapsible music holder comprising a standard composed of telescoping sections, a collapsible rack secured to the upper end of the uppermost of said sections, a slideable collar on the lowermost of said sections composed of a plurality of punchings fastened together, legs pivoted to said collar at the points where said punchings are fastened together, a similar collar composed of punchings fixed to said lowermost section at a point beneath said slideable collar, braces pivoted at one end to said fixed collar at the points where its punchings are fastened together and at the other end to intermediate points upon said legs, a leaf-spring catch formed integral with each of the punchings of said slideable collar and extending downward therefrom into a position to engage the corresponding punchings of said fixed collar when said legs are distended by the downward movement of said slideable collar, and a ring upon the lower end of said lowermost section having a limited slideable movement sufficient to engage said catches to free them from said fixed collar punchings to allow said legs to be collapsed by sliding said movable collar upward along said lowermost section.

4. A collapsible music holder comprising a standard composed of telescoping sections, collapsible supporting legs upon the lowermost of said sections, and a collapsible rack pivoted to the upper end of the uppermost of said sections comprising a central vertical member having two short vertical slots, two lower horizontal members pivoted at their inner ends to the lower end of said central vertical member and extending in opposite directions from it, two similar upper horizontal members pivoted at their inner ends to the upper end of said central vertical member and extending in opposite directions from it, pivots extending through the slots in said central vertical member and slideable therein, braces secured to said pivots at one end and pivoted to said upper hori-

- 2
- zontal members at the other, and braces secured to said pivots at one end and pivoted to said lower horizontal members at the other. 65
5. A collapsible music holder comprising a standard composed of telescoping sections, collapsible supporting legs upon the lowermost of said sections, and a collapsible rack pivoted to the upper end of the uppermost 70
- 10 of said sections comprising a central vertical member, two lower horizontal members pivoted at their inner ends to the lower end of said central vertical member and extending in opposite directions from it, two similar 75
- 15 upper horizontal members pivoted at their inner ends to the upper end of said central vertical member and extending in opposite directions from it, two outer vertical members pivoted at intermediate points of 80
- 20 their length to said lower horizontal members, horizontal extension members pivoted to the outer ends of said upper horizontal members, vertical extension members pivoted to the upper ends of said outer vertical members, said horizontal and vertical members 85
- 25 on each side of said central vertical member being pivoted together, two vertical links pivoted at their upper ends adjacent to the inner ends of said lower horizontal members, 90
- 30 shelf sections pivoted at their ends to the lower ends of said links and outer vertical members, and means for holding said horizontal members horizontal when said rack is in expanded position. 95
- 35 6. A collapsible music holder comprising a standard composed of telescoping sections, collapsible supporting legs upon the lowermost of said sections, and a collapsible rack pivoted to the upper end of the uppermost 100
- 40 of said sections comprising a central vertical member having two short vertical slots, two lower horizontal members pivoted at their inner ends to the lower end of said central vertical member and extending in opposite 105
- 45 directions from it, two similar upper horizontal members pivoted at their inner ends to the upper end of said central vertical member and extending in opposite directions from it, two outer vertical members 110
- 50 pivoted at intermediate points of their length to said lower horizontal members, horizontal extension members pivoted to the outer ends of said upper horizontal members, vertical extension members pivoted to 115
- 55 the upper ends of said outer vertical members, said horizontal and vertical members on each side of said central vertical member being pivoted together, two vertical links pivoted at their upper ends adjacent to the 120
- 60 inner ends of said lower horizontal members, shelf sections pivoted at their ends to the lower ends of said links and outer vertical members, pivots extending through the slots in said central vertical member and 125
- slidable therein, braces secured to said pivots at one end and pivoted to said upper horizontal members at the other, and braces secured to said pivots at one end and pivoted to said lower horizontal members at the other. 130
7. A collapsible music holder comprising a standard composed of telescopic sections, the first of said sections telescoping within the second, the second within the third and so on, one of said intermediate sections being enlarged at its lower end to closely fit the interior of the next section, a saw-cut in the enlarged end of said intermediate section, and said next section being contracted at its upper end to closely fit around said intermediate section at a point above its enlargement, whereby said sections are held in different adjusted positions by frictional engagement, and a stop-pin at the enlarged end of said intermediate section for limiting the movement of the section which moves into it; collapsible supporting legs upon the lowermost of said sections; and a collapsible rack secured to the upper end of the uppermost of said sections. 135
8. A collapsible music holder comprising a standard composed of telescopic tubular sections slidable into the lowermost section, a slidable collar on said lowermost section, legs pivoted to said collar, braces pivoted 140
- at one end to said legs and at the other end to said lowermost section at a point below said collar, and a collapsible rack having a central vertical member pivoted at its lower end to the upper end of the uppermost of said sections and being foldable forward against said legs and lowermost section when said standard and legs are in collapsed position, horizontal and vertical rack members on each side of said vertical member, and horizontal shelf members linked to said horizontal members, all of said shelf members and rack members being foldable into compact relation with said vertical member, whereby when all the parts are collapsed 145
- the horizontal portions of said shelf members will partially inclose the collapsed legs and standard. 150
9. A collapsible music holder comprising a standard composed of telescoping sections, collapsible supporting legs upon the lowermost of said sections, and a collapsible rack pivoted to the upper end of the uppermost of said sections comprising a central vertical member having two short vertical slots, two lower horizontal members pivoted at their inner ends to the lower end of said central vertical member and extending in opposite directions from it, two similar upper horizontal members pivoted at their inner ends to the upper end of said central vertical member and extending in opposite directions from it, pivots extending through 155

the slots in said central vertical member and
slidable therein, braces secured to said piv-
ots at one end and pivoted to said lower
horizontal members at the other, and mem-
bers pivoted at one end to said upper hori-
zontal members and coöoperating with said
braces and lower horizontal members to
maintain said upper horizontal members

horizontal when the rack is in open position.

In witness whereof, I hereunto subscribe 10
my name this 17th day of March, 1911.

LEWIS A. BRINKMAN.
